APPARATUS FOR TAKING SAMPLES
FROM WELLS

Walter L. Church, Houston, Tex.

Application August 31, 1934, Serial No. 742,300

6 Claims. (Cl. 255—1)

This invention relates to an apparatus for taking samples from wells.

An object of the invention is to provide a device of the character described specially designed for the purpose of taking samples of the formation of the walls of a well bore and for withdrawing the samples taken to the ground surface for inspection so as to determine the character of the strata pierced by the bore.

Another object of the invention is to provide a device of this character adapted to be let down into and withdrawn from a well bore by means of a cable or other flexible line.

A still further feature of the invention resides in the provision of an apparatus for taking wall samples which will be in collapsed or inactive position while being lowered, but which is under the control of the operator to be actuated into active position, when desired, to collect samples of the wall structure and which may be thereupon again collapsed or moved to inactive position for withdrawal.

With the above and other objects in view, the invention has particular relation to certain novel features of construction, operation and arrangement of parts, an example of which is given in this specification and illustrated in the accompanying drawing, wherein:

Figure 1 shows a side view of the apparatus shown partly in section, and in active position.

Figure 2 shows a cross sectional view taken on the line 2—2 of Figure 1.

Figure 3 shows a cross sectional view taken on the line 3—3 of Figure 1, and

Figure 4 shows a side view of the apparatus partly in section, and in inactive position.

In the drawing the numeral 1 designates the main body of the apparatus which is preferably cylindrical and whose upper end has an outwardly threaded pin 2 to receive the conventional rope socket 3 to which the lower end of the operating cable 4 is attached. The apparatus is let down into and withdrawn from the well bore by means of this cable which is operated by any suitable equipment at the ground surface designed for the purpose. Attached to the lower end of the body there is a tubular shell 5 within which there is an elongated metal core 6, forming a weight. A cross pin 7 extends through said core and its free ends work in the vertical side slots 8 of the shell.

Suitably fastened to the shell 5 there is a housing 9 which encloses the solenoid windings 10. A tubular guide plug 11 is screwed onto the lower end of the shell and closes the lower end

of the housing 9. The windings 10 are thus completely enclosed and protected. A current conductor 12 leads from the ground surface down through the body 1 and shell 5 and is connected to the windings 10. This current conductor may form the core of the cable 4, if desired, and is provided with a detachable connection 13 within the rope socket. The body 1 is formed with a surrounding anchor 14, preferably formed integrally therewith to which the upper ends of the 10 toggle arms 15 are pivoted. The lower ends of these toggle arms 15 are connected by the toggle links 16 to the sliding collar 17 which is located on the shell beneath the body and which is slidable thereon. The ends of the pins 7 are anchored to this sliding sleeve 17.

The arms 15 have the pockets 18. These pockets are inclined downwardly and inwardly and they are also contracted downwardly and inwardly as more clearly illustrated in Figure 1. 20 The outer margins of the lower ends of the blades extend vertically when the device is in active position forming the wall runners 19 whose upper ends terminate in the cutting or scraping edges 20 beneath the outer ends of the respective 25 pockets.

When the apparatus is lowered into the well the circuit through the conductors 12 is broken by a suitable switch at the ground surface. The core 6 will then be in its lower position with the 30 cross pin 7 hanging on the lower ends of the slots 8 and the sleeve 17 will move downwardly with the core 6 into its lower position as shown in Figure 4 and the toggle levers 15 will thereby be moved into inactive or collapsed position so 35 that they will be clear of the bore walls. When the apparatus is located at the desired place the switch at the ground surface may be closed thereby energizing the solenoid coils 10 and the core 6 will be lifted into the position shown in Figure 40 1 thus moving the sleeve 17 upwardly and acting through the toggle links 16 to move the toggle levers 15 outwardly into active position with the runners 19 against the walls of the bore. The apparatus may then be elevated by means of the 45 cable 4 and the blades or scrapers 20 will penetrate into the wall formation and scrape or shave off samples of said formation which will be directed into the pockets 18. The slime or other liquid matter adhering to the walls of the bore 50 and directed into said pockets will drain out of the pockets at their contracted lower ends but the solid formation will pack in said pockets and be retained therein. The conductor 12 may then again be broken by opening the switch at the 55

ground surface and the core 6 will then drop collapsing the device and it may then be withdrawn to the ground surface for an inspection of the sample. The conductor 12 and winds 10 are 5 suitably insulated.

The apparatus may be lowered into the bore and manipulated from time to time so as to take samples of the bore walls throughout any desired area of said walls.

10 What I claim is:

1. Apparatus for taking a sample from a well comprising a supporting structure, sample receiving and retaining means on the supporting structure movable into active, or outer position, and movable into inner or inactive position, said receiving and retaining means having a sample receiving pocket and a deflector arranged to sever a wall sample and direct the same into the pocket, and electrically operable means under 20 the control of an operator and effective to move the sample receiving and retaining means into said active position.

2. Apparatus for taking a sample from a well comprising a support, a device thereon movable into expanded, or active, position and also movable by gravity into collapsed, or inactive, position, said device being provided with a sample receiving pocket and a deflector adjacent the pocket, electrically operable means effective to 30 move the device into active position whereby, upon upward movement the deflector will engage the walls of the well and sever a sample and direct the sample into the pocket.

3. Apparatus for taking a sample from a well 35 comprising a support, means thereon swingable into outer, or active position into cooperating relation with the wall of the well, an electrically operable device under the control of an operator for moving said means into said active position, said means having a sample receiving pocket and a deflector adjacent the outer end of the pocket

effective, upon upward movement of the apparatus in the well, to sever a wall sample and direct the sample into said pocket.

4. Apparatus for taking a sample from a well 5 comprising a support, means thereon swingable into outer, or active position into cooperating relation with the wall of the well, an electrically operable device under the control of an operator for moving said means into said active position, said means having a sample receiving pocket and 10 a deflector adjacent the outer end of the pocket effective, upon upward movement of the apparatus in the well, to sever a wall sample and direct the sample into said pocket, and means affected by gravity for moving said means into inactive 15 position.

5. Apparatus for taking a sample from a well comprising a support, means thereon swingable into outer, or active position into cooperating 20 relation with the wall of the well, an electrically operable device under the control of an operator for moving said means into said active position, said means having a sample receiving pocket and a deflector adjacent the outer end of the pocket 25 effective, upon upward movement of the apparatus in the well, to sever a wall sample and direct the sample into said pocket, said pocket having a drain outlet to permit the drainage of liquid from the sample.

6. Apparatus for taking a sample from a well 30 comprising a support, a device thereon movable into outward, or active position, and also movable by gravity into inner, or inactive, position, said device having a sample-receiving pocket and 35 wall-engaging means adjacent the pocket, electrically operable means effective to move the device into outward position whereby, upon upward movement, the wall-engaging means will sever a sample and direct the same into the pocket.
